UNITED STATES PATENT OFFICE.

SIGMUND V. HUBER, OF YOUNGSTOWN, OHIO.

ROLLING-MILL.

SPECIFICATION forming part of Letters Patent No. 650,682, dated May 29, 1900.

Application filed December 29, 1898. Serial No. 617,329. (No model.)

To all whom it may concern:

Be it known that I, SIGMUND V. HUBER, a citizen of the United States, residing at Youngstown, in the county of Mahoning and State of Ohio, have invented or discovered certain new and useful Improvements in Rolling-Mills, of which improvements the following is a specification.

The invention described herein relates to 10 certain improvements in feed-tables for rolling-mills, whereby an article may be passed back and forth successively through different passes in the rolls and whereby each article may be succeeded by another article in quick 15 succession, so that a series of three or five or more articles may be in the process of reduction simultaneously by the same set or stand of rolls.

The invention is hereinafter more fully described and claimed.

In the accompanying drawings, forming a part of this specification, Figure 1 is a top plan view of a rolling-mill having my improved feed-table applied thereto. Fig. 2 is 25 a top plan view of the roller's table, and Fig. 3 is a similar view of the catcher's table. Fig. 4 is a sectional elevation, the plane of section being indicated by the line IV IV, Fig. 1, and passing through the second pass of the catcher's table and the third pass of the roller's table. Fig. 5 is a sectional elevation, the plane of section being indicated by the line V V, Fig. 2, and passing through the first pass of the roller's table. Figs. 6, 7, and 8 are 30 sectional elevations, the planes of section being indicated by the lines VI VI, VII VII, and VIII VIII, Fig. 2, and passing, respectively, through the second, fourth, and fifth passes of the roller's table. Fig. 9 is a plan view, 35 the feed-rollers being removed to show the transfer mechanism. Fig. 10 is a sectional elevation, the plane of section being indicated by the line X X, Fig. 2. Fig. 11 is a similar view, the plane of section being indicated by 40 the line XI XI, Fig. 2. Fig. 12 is a transverse sectional elevation, the plane of section being indicated by the line XII XII, Fig. 2. Fig. 13 is a diagrammatic view showing the horizontal movements of articles through my 45 improved mill.

In the practice of my invention I employ a three-high mill having passes so arranged that

the first, third, and fifth passes will be between the lower and middle rolls and the second and fourth passes between the middle 55 and upper rolls. On opposite sides of such a three-high mill are placed what I term the "roller's" and "catcher's" tables. As these tables are similar in construction except for a few minor features of construction, as will 60 be hereinafter pointed out, the description will refer only to the roller's table.

Upon the sides of a suitable frame 1 are secured the bearings 2 for the feed-rollers 3, which extend entirely across the frame 1 and 65 are of a length approximately equal to the length of the reducing-rolls. As hereinafter described, the end and middle portions of these rollers are employed for feeding the article to be rolled into the first, third, and 70 fifth passes of the reducing-rolls, while portions intermediate of the end and middle portions are employed for driving feed-rollers 4 and 5, which serve to feed the article into the second and fourth passes between the upper 75 and middle rolls of the reducing-mill.

As shown in Figs. 4, 5, 6, 7, 8, and 11, a trough-like brace is arranged between the sides of the frame 1 in line with the feed-rollers 3, which are partially inclosed by such 80 trough-like braces 6. In order to support the article being rolled intermediate of the rollers, aprons 7 are secured to the outturned flanges 6^a along the upper edges of the brace 6, said aprons extending between the rollers 85 at the ends thereof or portions in line with the first and fifth passes of the reducing-rolls, as shown in Figs. 5 and 8. Similar aprons 10 are arranged between the middle portions of rollers 3, forming a third pass, where said 90 rollers are separated a sufficient distance to render an intermediate support unnecessary. In order to prevent the article being rolled from moving laterally off of the rollers, side guides 8 are secured to the apron 7 by means 95 of bolts, whose heads are arranged in undercut grooves 9, formed in the aprons 7, as shown in Figs. 1, 2, 3, 5, and 8. This construction or manner of supporting the side guides 8 permits of their adjustment transversely of the aprons in accordance with the width of the article to be rolled. Vertical walls 11 and 12 are arranged upon the cross-braces 6 in line or approximately in line with

the ends of the grooves forming the second and fourth passes in the reducing-rolls, as clearly shown in Fig. 11. Between these walls are arranged the rollers 4 and 5, the journals 5 of said rollers entering vertical grooves in the inner faces of the walls 11 and 12, said grooves being made of sufficient length to permit the rollers to rest upon the main rollers 3, whereby the rollers 4 and 5 are rotated. As shown 10 in Figs. 6, 7, 9, and 11, side guides 13 and 14 are arranged upon the walls 11 and 12, said guides projecting up a sufficient height to insure the retention of the article being rolled in line with the passes 2 and 4 of the reducing-rolls. Integral with these guides are formed aprons 15, which extend each way from opposite sides of the rollers toward the adjacent rollers, so as to nearly bridge the spaces between such rollers.

20 It will be observed by reference to Figs. 4, 6, 7, and 8 that the rollers are arranged comparatively close together for the first, third, and fifth passes of the roller's table, but are farther apart in the second and fourth passes 25 of the same table, the reason for such construction being that the first, third, and fifth passes of the roller's table are what might be termed "feed-passes"—i. e., the article is moved from such passes to the reducing-rolls—while the second and fourth passes are receiving-passes, the article being forced into such passes by the reducing-rolls. In the catcher's table these constructions are reversed, the second and fourth passes thereof 35 being feed-passes, while the first, third, and fifth passes are receiving-passes.

In order to transfer the article being rolled from the second to the third and from the fourth to the fifth passes of the roller's table 40 and from the first to the second and from the third to the fourth passes of the catcher's table, any suitable form or construction of transfer mechanism capable of vertical and lateral movement may be employed—such, for 45 example, as that shown in Figs. 4, 9, and 10. As clearly shown in Fig. 11, this transfer mechanism consists of heads 16, provided with upwardly-projecting prongs 17, which are secured upon the upper end of a vertically-movable standard 18, which is arranged in suitable guides secured to a transverse beam of the frame 19. The number of these lifting devices employed is dependent upon the length and thickness or rigidity of the article operated on, the longer and thinner the article 55 the greater the number of lifters which should be employed. The frame 19 is made of such a length compared with the length of the feed-tables as will accommodate the required number of lifters, and the transverse beams supporting the guides 18 of the lifters are arranged at suitable intervals along the frame 60. At suitable intervals the side bars of the frame 19 are provided with laterally-projecting lugs 20, whose outer ends are suitably shaped to form bearings for the wheels 21, which are supported upon rails 22, arranged

transversely of the feed-tables, below the rollers 3 thereof. As shown in Figs. 1, 2, 3, and 9, the frame 19 is connected by rods 23 to crank-arms 24, secured upon a shaft 25, which preferably extends the entire length of the mill. This shaft 25 is rotated to shift the frame 19 through the mechanism described by means of a fluid-pressure engine 26, having its piston-rod 27 connected by rods 28 to a crank-arm on the shaft 25. In order to effect the vertical movement of the standards 18 and the heads 16, shafts 29 are mounted in suitable bearings longitudinal of the frames 80 19, and on said shafts are secured the pinions 30, adapted to intermesh with rack-bars 31 on the standards 18. It is preferred to form the standards with a vertical slot and to arrange the rack-bars on the inner walls thereof, 85 as clearly shown in Figs. 9 and 10. As shown in Figs. 1, 2, and 4, these lifters are arranged to operate between adjacent feed-rollers 3, 4, and 5, and the heads 16 of such lifters are arranged a distance apart approximately equal 90 to the distance between the second and fourth passes of the roller's table and the first and third passes of the catcher's table. As will be seen by reference to Fig. 1, the lifting devices are arranged so as to transfer an article 95 laterally from the second and fourth passes of the roller's table and downwardly to the third and fifth passes of the same table, whereas in the catcher's table the lifters are arranged to lift the article from the first and third passes and move it laterally to the second and fourth passes.

In order to rotate the shaft 29, whereby the lifters are raised and lowered, pinions 32 are secured upon the shafts 29, and with said pinions the rack-bar 33 intermeshes. This rack-bar is connected to the piston 34 of the fluid-pressure cylinder 35, which is movably mounted in guides 36, arranged upon a suitable foundation adjacent to the feed-tables. The 100 fluid-pressure cylinder 35 is tied in suitable relation to the frame 19 so as to move therewith by means of rods 37, secured at their ends to the cylinder and frame 19, as clearly shown in Fig. 9.

115 In normal position of the transfer mechanism the heads 16 of the roller's table are in line with the feed-rollers 4 and 5, forming the second and fourth passes of said table, and the heads 16 of the catcher's table are in line 120 with the first and third passes thereof. In operating my improved mill an article is placed on the ends of the feed-rollers 3 of the roller's table in line with the first pass of the reducing-rolls and is delivered by the latter 125 to the first pass of the catcher's table. The transfer mechanism is now operated to raise the article and shift it laterally onto the rollers 4, forming the second pass of the catcher's table. The transfer mechanism is returned to normal position. A second article is placed in the first pass of the roller's table. As soon as the articles are deposited on the continuously-operating feed-rollers the first

article is fed into the second pass of the reducing-rolls and the second article into the first pass of the reducing-rolls. The rolls deliver the first article into the second pass of the 5 roller's table and the second article into the first pass of the catcher's table, respectively. The transfer mechanism is again operated to shift the first article to the third pass of the roller's table and the second article to the second pass of the catcher's table. After the transfer mechanism has been returned to normal position a third article is placed in the first pass of the roller's table. By the operation of the feed-rollers the first 15 and third articles are fed into the third and first passes of the reducing-rolls and the second article to the second pass of the reducing-rolls.

By the action of the rolls the third and first 20 articles are fed into the first and third passes of the catcher's table and the second article into the second pass of the roller's table. The transfer mechanism is now operated to shift the first and third articles to the second 25 and fourth passes of the catcher's table and the second article to the third pass of the roller's table and then returned to normal position. A fourth article is then placed upon the first feed-pass of the roller's table, and 30 by the action of the feed-rollers the first and third articles are fed to the fourth and second passes of the roller's table and the second and fourth articles to the third and first passes of the catcher's table. The transfer mechanism 35 is again operated so as to shift the first and third articles onto the fifth and third passes of the roller's table and the second and fourth articles onto the fourth and second passes of the catcher's table. After the transfer mechanism has been returned to normal 40 position a fifth article is placed in the first pass of the roller's table. By the operation of the feed-rollers the first, third, and fifth articles are fed through the reducing-rolls 45 into the fifth, third, and first passes of the catcher's table, and the second and fourth articles are fed through the reducing-rolls into the fourth and second passes of the roller's table. The first article, which has now 50 passed through the successive reducing-passes of the rolls, is removed by any suitable means from the fifth pass of the catcher's table, and the transfer mechanism is operated to shift the second and fourth articles 55 onto the fifth and third passes of the roller's table and the third and fifth articles onto the fourth and second passes of the catcher's table and then returned to normal position. A sixth article is now placed in the first feed-60 pass of the roller's table, and the second, fourth, and sixth articles are fed by the rollers through the reducing-rolls into the fifth, third, and first passes of the catcher's table and the third and fifth articles through the 65 reducing-rolls to the fourth and second passes of the roller's table.

From the foregoing it will be understood

that after the first article has reached the fifth pass of the roller's table five articles will be in the course of reduction simultaneously 70 by the mill, a new article being placed after each operation of the transfer mechanism in the first pass of the roller's table.

In order to facilitate the operation of the mill, a series of movable stops or abutments 75 38 are arranged at suitable intervals in the line of movement of articles in the first pass of the roller's table, one of said stops being located near the end of the roller's table adjacent to the reducing-rolls. These stops or abutments are preferably made in the form of arms keyed to shafts 39, which are mounted in suitable bearings 40, secured to the sides of the frame of the feed-table. In order to relieve shocks or jars incident to the 80 impact of an article against the stops, the shafts 39 are removable longitudinally in their bearings, and springs 41 are interposed between one of the bearings and collars 42 on the shafts. In order to render the lifting 85 of the stops or abutments easy, counterweights 43 are attached to arms 44, projecting from the shafts 39 in a direction opposite to that of the arms 38. As will be readily understood, these stops or abutments render 90 it possible to place a number of articles upon the portions of the rollers 3 forming the first pass of the roller's table and hold them in position to be fed into the reducing-rolls until after the operation of the transfer mechanism 95 has been effected. As soon as the stop or abutment adjacent to the reducing-rolls has been lowered after the passage of an article into the reducing-rolls the other stops or abutments can be raised, permitting the 100 forward movement of all articles resting on the feed-rollers one step or stage toward the reducing-rolls.

In order to insure the simultaneous operation of the transfer mechanism on each side 110 of the reducing-rolls, the shafts 29 under each of the feed-tables are provided with pinions 45 on their inner ends, adapted to intermesh with corresponding pinions 46 on the shaft 47, extending under the reducing-rolls, as 115 clearly shown in Fig. 4.

I claim herein as my invention—

1. The combination of a three-high mill having three or more reducing-passes, three or more series of driven feed-rollers in line with 120 said passes on each side of the mill, mechanism for driving two or more of said series of rollers on each side in one direction and one or more of the series on each side in an opposite direction, a mechanism on each side of 125 the mill for transferring an article from one series of feed-rollers to the next adjacent series, and means for simultaneously operating both transfer mechanisms, substantially as set forth.

2. The combination of a three-high mill having two or more reducing-passes in one horizontal plane, and one or more passes in a different horizontal plane, a series of driven

feed-rollers on each side of the mill, said rollers being of sufficient length to extend in front of two or more passes of the reducing-rolls, a series of driven feed-rollers on each side of the mill in a different horizontal plane from the first series, of sufficient length to extend in front of one or more passes, and mechanism on each side of the mill for moving an article vertically and laterally, substantially as set forth.

3. The combination of a three-high mill having two or more reducing-passes in one horizontal plane and one or more passes in a different horizontal plane, a series of positively-driven feed-rollers on each side of the mill, said rollers being of sufficient length to extend in front of two or more passes of the reducing-rolls, a series of feed-rollers on each side of the mill in a different plane from the first series and driven by the rollers of the first series, the rollers of the second series be-

ing of a length sufficient to extend in front of one or more passes of the reducing-rolls, and mechanism on each side of the mill for moving an article vertically and laterally, substantially as set forth. 25

4. The combination of a three-high mill, three or more series of driven feed-rollers arranged in different horizontal planes on each side of the mill, a transfer mechanism on each side of the mill, means for simultaneously shifting both transfer mechanisms laterally and means for simultaneously raising and lowering both transfer mechanisms, substantially as set forth. 30

In testimony whereof I have hereunto set my hand. 35

SIGMUND V. HUBER.
